THOMAS S. MONAGHAN, OF CORINTH, MISSISSIPPI, ASSIGNOR OF ONE-HALF TO
GEORGE E. OLMSTED, OF DANVILLE, ILLINOIS.

DUST SEPARATOR AND COLLECTOR.

Application filed May 24, 1927. Serial No. 193,890.

This invention relates to the class of gas separators and pertains particularly to a separator designed to remove dust and dirt from air.

5 The primary object of the present invention is to provide, in a manner as hereinafter set forth, a dust separator of improved construction capable of handling a large quantity of air and of separating dust and other solid 10 particles therefrom with the use of a relatively low air pressure for driving the air into the separator.

Another object of the invention is to provide, in a manner as hereinafter set forth, a 15 dust collector of such construction as to offer a minimum amount of back pressure with a maximum of dust separating efficiency.

A still further object of the invention is to provide a structure of the character above set 20 forth which is of strong and durable and simple construction, and comparatively inexpensive to manufacture and set up.

Numerous other objects and advantages of the present invention will become apparent as 25 the description of the same proceeds and the invention will be best understood from a consideration of the following detailed description taken in connection with the accompanying drawing forming a part of this specification. 30 With the understanding, however, that the invention is not confined to any strict conformity with the showing of the drawing but may be changed or modified so long as such changes or modifications mark no material 35 departure from the salient features of the invention as expressed in the appended claims.

In the drawings:

Figure 1 shows the structure embodying this invention in side elevation.

40 Figure 2 is a central longitudinal section of the structure.

Figure 3 is a central longitudinal section taken at right angles to the section shown in Figure 2.

45 Figure 4 is a top plan view of the separator structure, and

Figure 5 is a section taken transversely of Figure 3 on the line 5—5.

Referring now to the drawings in detail, 50 wherein like numerals of reference indicate corresponding parts throughout the several views, the numeral 1 indicates the body of the structure which, as shown, is of cylindrical construction and is adapted or intended to be 55 mounted in vertical position as shown. The

upper portion of the body 1 has the top closure structure 2 which is of frusto-conical design and has extending through the central portion thereof the vertically arranged short outlet pipe 3. As is clearly shown in Figures 60 2 and 3, this outlet pipe extends longitudinally of and into the main body or housing 1 to a point adjacent the central portion thereof.

The lower edge of the housing 1 is provided 65 with the laterally directed surrounding flange 4 which rests upon the annular collar 5 of a supporting structure which comprises in association with the collar 5, the legs 6, the upper ends of which extend into and are secured to the collar as shown.

Surrounding the legs 6 adjacent the lower 70 ends thereof is a second collar or retaining band 7 which maintains the legs in spaced relation, as will be readily understood.

While applicant has shown and described 75 a particular means for a dust separator structure in the proper upright position, it is to be understood that he does not wish to limit himself to the employment of such a supporting structure for any appropriate supporting means may be employed.

Forming the lower portion of the separator structure is an inverted frusto-conical body or funnel 8, the periphery of the base of 80 which is arranged in abutting relation to the lower edge of the cylindrical body 1 while the lower constricted open end has the longitudinally aligned discharge collar 9 opening 85 therefrom, to which collar an appropriate lead-off pipe line may be attached as is obvious for conducting the separated dust away 90 from the separator.

The outlet cone 8 is preferably of the same 95 or slightly greater length than the body cylinder 1 as it has been found that this proportioning of the sections of the structure gives the best results.

Within the lower portion of the body 1 and 100 arranged concentric therewith is an annular body 10 in the form of a band which is of materially less diameter than the interior diameter of the body or casing 1 leaving an annular passage-way 11 between this band and the wall of the casing. A plurality of 105 spacing sleeves are arranged between the band 10 and the wall of the casing as indicated by the numeral 12, and through these sleeves appropriate securing bolts 13 are passed, the ends of which pass through the 110

band and casing wall as shown, to secure the same together.

Secured to the air outlet pipe 3 at the inner end of the same and preferably to the inner 5 face thereof, is a plurality of supporting arms 14 which are arranged in circular formation and extend longitudinally through the casing and terminate in the upper portion of the dust discharge or outlet cone 8. The terminal 10 portions of the arms 14 are directed slightly inwardly as indicated at 15 and carry thereon the surrounding tapered cylinder 16, the lower or constricted end of which terminates a slight distance inwardly of the terminal 15 ends of the portions 15 of the arms while the upper end terminates in substantially the same plane as the upper edge of the band 10.

The lower terminals of the arms 14 are secured to and support an upright and relatively 20 flat cone body 17, which body has its apex in alignment with the longitudinal center of the separator structure and thus directly covers but is spaced a substantial distance from the outlet sleeve 9 of the cone 25 body 8.

Formed in the wall of the body 1 is an inlet opening 18 and secured to the body in tangential relation thereto and overlying and opening thereto through the opening 30 18 is the air admission pipe 19 through which air to be cleansed is conducted to the interior of the separator. As shown, the major portion of the inlet opening 18 is above the lower end of the outlet pipe 3.

In operation, the dust laden air entering the body 1 through the tangentially arranged line 19 will be caused to whirl about the interior of the casing setting the entire air contents of the separator in rotary motion. The 35 dust particles through gravitational attraction will fall through the annular passage-way 11 to the cone 8 and the air will pass upwardly through the cylinder 16 and the outlet pipe 3. The cone 17 will act to direct the 40 air in a stream through the central portion of the structure and upwardly therethrough. The separated dust will fall into the cone and be led therefrom through the sleeve 9 and an appropriate lead-off pipe or other means as- 45 sociated therewith.

Having thus described my invention, what I claim is:

1. In a dust separator of the character described, a cylindrical upright casing, a 55 frusto-conical head upon the upper end of said casing, an air outlet pipe opening through the central portion of said head, and terminating at its inner end adjacent the central portion of the casing, an inverted 60 substantially frusto-conical dust discharge

funnel having the base abutting the lower edge of said cylindrical casing, an outlet sleeve opening through the central portion of said inverted frusto-conical body, an annular body of materially less diameter than and concentrically arranged within said casing, means for admitting air to said casing tangentially through the wall thereof, means suspended from the lower end of said outlet pipe for setting up an upwardly directed stream or current for discharge through the outlet pipe, and a tapered guide cylinder arranged between said air directing means and the outlet pipe having the upper end of greater diameter than the lower end thereof and arranged in alignment with said outlet pipe.

2. In a dust separator of the character described, comprising a vertically arranged cylindrical body, a head in the upper end of said body of frusto-conical formation, a longitudinally directed centrally disposed outlet pipe extending through said head and terminating at its inner end adjacent the central portion of said body, a dust discharge funnel of inverted substantially conical form arranged beneath and opening into the casing and having an outlet at its lower central portion, an annular band of materially less diameter than and arranged concentrically within the cylindrical casing, depending supporting arms carried by said outlet pipe and extending through said annular band, an upright cone body carried by the lower ends of said arms in alignment with the outlet openings, a tapered guide cylinder carried by and surrounding said arms between the first mentioned outlet pipes and said cone body, and means for admitting air to said cylinder body tangentially to the wall thereof.

3. In a dust separator, a casing having an inlet, an air outlet and a dust outlet in alignment, an outlet pipe in the casing in longitudinal alignment with the outlets, a tapered guide cylinder in spaced longitudinal alignment with the air outlet pipe, with the constricted end directed therefrom, an upright cone body arranged in spaced aligned relation with the constricted end of the guide cylinder, and an annular band of constant diameter throughout and materially less diameter than the casing, arranged within the casing and concentric with the outlet pipe and further being positioned in substantially the same plane as the larger end of the tapered guide cylinder.

In testimony whereof I affix my signature.

THOMAS S. MONAGHAN.
